UNITED STATES PATENT OFFICE.

BAPTISTE ICRE, OF NEW YORK, N. Y.

PROPELLER FOR VESSELS.

Application filed July 1, 1916. Serial No. 107,017.

To all whom it may concern:

Be it known that I, BAPTISTE ICRE, a citizen of the French Republic, and resident of the borough of Manhattan, city, county, and State of New York, have invented certain new and useful Improvements in Propellers for Vessels, of which the following is a specification.

My invention relates to propellers of the feathering-blade type for vessels of various characters, whether intended to navigate on or below the surface of the water. My present invention contemplates further improvements in propellers of the class disclosed in my earlier Patents No. 976,178 of November 22, 1910, and No. 1,182,014 of May 9, 1916. In this class of propellers, the blades, as they revolve about the axis of the propeller, are turned at the proper time about their individual axes, by the action of a normally stationary cam. The purpose of my present improvements is to secure better and more varied results in the operation of the propeller, by a novel construction and arrangement of the said cam, the invention also consists of other novel features which will be fully set forth in the description following hereinafter, and specifically pointed out in the appended claims.

Reference is to be had to the accompanying drawings, in which Fig. 1 is a side elevation of a ship (for water navigation) having my improved propellers applied thereto; Fig. 2 is a plan view thereof; Fig. 3 is a rear elevation of such ship; Fig. 4 is a rear elevation showing a slightly different arrangement, such as may also be employed in conjunction with vessels of various types; Fig. 4^a is a diagrammatic plan view of a submarine, showing one arrangement of propellers therefor; Fig. 5 is a diagrammatic developed view illustrating the manner of swinging or "feathering" the blades, say from a horizontal to a vertical position and vice-versa; Fig. 6 is a partial sectional plan showing two stern propellers; Fig. 7 shows upon an enlarged scale a preferred form of my improved propeller; Fig. 8 is a horizontal section on the line 12—12 of Fig. 7, looking upward; Fig. 9 is a partial side elevation taken in the direction of the arrow 13 in Fig. 7; Figs. 10 and 11 are partial developed views of the cam-track employed in Fig. 7, illustrating two different positions of said track; Fig. 12 is a series of diagrams illustrating different positions

which may be taken by the adjustable track of Figs. 7 to 11 inclusive, and also indicating the blade movements resulting from such positions.

In Figs. 1 and 2 I have indicated an ocean liner A provided amidships with propellers a^1 and a^2 of my improved type located at each side, and at the stern with propellers b^1 and b^2 (likewise of the improved type) in a relative position corresponding to that of the well-known twin-screw propellers. In Fig. 3, the ship's hull is provided with tunnels beneath the propellers b^1 , b^2 , to contain part of the machinery, while in Figs. 4, 4^a, and 7 the lower faces of the propellers are fully exposed.

Referring to the detail construction shown in Fig. 7, the device comprises a hollow main-shaft 20 extending vertically, and supported in suitable bearings (not shown). To the upper extremity of said shaft is secured rigidly a bevel gear 25, in mesh with a bevel pinion 25^a on a shaft 25^b operated from the driving shaft of the engine in any suitable manner. To the lower end of the shaft 20 is secured a cap or closure 26 which serves to prevent the access of water to the operating parts, and also to support and retain a body of lubricant, so that the operating parts may run in oil or the like. At the lower end of the shaft 20 are provided radial enlargements or hubs 27, in which are supported the shanks of the feathering blades 27^a, by means of ball-bearings 27^b, suitable packings, which are held in position by nuts or caps 27^c, being provided in the hubs to prevent the entrance of water into the hollow main-shaft. Within the shaft 20 is arranged centrally or axially, a normally stationary shaft 28, supported at its lower end in an anti-friction neck-and-step bearing 28^a provided on the inner side of the closure 26. Bevel-gears 28^c and 28^d, applied at the upper end of said center-shaft 28, serve to turn the latter, when desired, for a purpose to be stated presently. The closure 26 is also shown as forming with the shaft 20, an annular groove or catch-recess to receive metal-chips or grit from the machinery, and prevent them from reaching the bearing 28^a.

On the lower portion of the center-shaft 28 are mounted certain parts forming a normally stationary cam-track held to turn with the shaft 28. This cam-track might be secured to said shaft rigidly, as indicated or suggested at 29 in Fig. 6, such track being

composed of a relatively short horizontal lower portion (*m* in diagram I, Fig. 12), a relatively long horizontal upper portion (*n*), and two inclined connecting or intermediate portions (*o*). The cam-track shown in Figs. 7 to 11, is of a somewhat different construction, as will be described below, but in the position shown in Figs. 7 to 10 inclusive, it has the same characteristics of shape (diagram I, Fig. 12) and the same function as the track secured rigidly to the shaft 28, that is to say, it has a relatively short horizontal lower portion, a relatively long horizontal upper portion, and two oppositely-inclined connecting or intermediate portions. Between the flanges which form the cam-track are guided slide-blocks or shoes 30 which are applied pivotally to the wrist-pins 30^a of cranks 30^b, keyed or otherwise secured to the reduced inner ends of the shanks of the blades 27^a. As the hollow main-shaft 20 is rotated (the center-shaft 28 and the cam-track connected therewith remaining stationary), the slide-blocks 30 will travel between and along the cam-flanges of said track-sections. As long as the slide-blocks 30 are at the relatively long upper portions *n* (Fig. 5) of the cam-track, the blades 27^a will be horizontal, as shown at the right in Fig. 7, and when the slide-blocks travel along the inclined cam-portions *o*, (Fig. 5) the blades will be turned gradually on the axes of their shanks, and when the slide-blocks reach the relatively short lower portion *m* (Fig. 5) of the cam-track, the blades 27^a will assume a vertical position, as shown at the left in Fig. 7. The well-known feathering action is thus obtained, by which the vessel is propelled forward if the shaft 20 is rotated in the proper direction for this purpose.

The shaft carrying the bevel-gear 28^a may be turned by means of suitable mechanism (not shown), such mechanism being preferably so constructed that the shaft 28 may be given a definite angular movement of 90°, 180°, 270°, or 360°. For relatively small vessels, this mechanism for turning or adjusting the center-shaft 28 may be operated by hand, say by providing a suitable crank-handle or the like on the shaft of the bevel-gear 28^a; for larger vessels, this shifting or adjusting mechanism would be operated by power derived from the engine. According to the adjustment of the center-shaft with the cam-track carried thereby, different results would be obtained: thus, if we assume that the vessel will be propelled forward with the shaft 28 in the position which produces the operation illustrated by Fig. 6, then by turning the shaft 28 through an angle of 180°, it will be given a position which will cause the vessel to be reversed, or backed astern, with the main-shaft 20 rotating in the same direction as before. If the

shaft 28 is turned through an angle of 90° or 270° from the position which produces the operation indicated in Fig. 6 (with the main-shaft 20 still rotating in the same direction), the result will be a swinging of the vessel to port or starboard, that is to say, the propeller will assist the action of the rudder, or steering may be accomplished without the use of the rudder, through the sole action of the propellers. 75

When the improved propeller is used in cases where a raising or lowering effect is desired at times, as in submarines, one or more of these propellers can be used, applied below the hull of the vessel in the center or at each side. Thus, a submarine might have two propellers of the character represented in Figs. 7 to 11, placed below the hull at points corresponding to the location of the propellers *a*¹, *a*² of Figs. 1 and 2, that is to say, at or near the transverse plane containing the center of gravity. Or I might adopt other arrangements, an instance of which is shown in Fig. 4^a, where I show two stern propellers *b*¹, *b*² (rotating in opposite directions) located in the same transverse plane, and two bow propellers *c*¹, *c*² (likewise rotating in opposite directions) located one in advance of the other in the longitudinal center of the vessel. The details shown in Figs. 7 to 11 apply to all the propellers of Fig. 4^a, it being understood that each of these propellers has its lower surface fully exposed to the water, below the hull of the submarine. 95

The arrangement shown at *a*¹, *a*² in Figs. 1 and 2, or the arrangement of bow and stern propellers shown in Fig. 4^a, has the advantage of enabling the ship to be quickly swung or "pivoted" in situ or nearly so, about an axis passing vertically through the center of gravity, or close thereto. 105

In addition to this, the propeller construction indicated in Fig. 4^a, and shown in detail in Figs. 7 to 11 inclusive, enables the boat to be moved quickly in an upward direction, say to bring a submarine to the surface, or in a downward direction when it is desired to make the boat "dive," that is to say, submerge it to a greater or less depth. 110 I desire it to be understood that the detail construction of the propeller illustrated by Figs. 7 to 11 may be applied in other ways than indicated in Fig. 4^a or suggested above, in connection with the propeller location *a*¹, *a*² of Figs. 1 and 2. For the purpose of exerting the lifting or lowering action on the boat, as referred to above, the blades 27^a must not stand vertical at the time of their active or flatwise movement, but in a position inclined to the horizontal, say at 45°, so that each blade impulse will have a component tending to raise or lower the ship. 115 I may employ any suitable mechanism for giving the blades this position in which they 120

have a lifting or lowering effect. Thus, Figs. 7 to 11 inclusive show the center-shaft 28 provided with a cam-track of the general character set forth above, but the said track, while compelled to turn with the center-shaft, is composed of two sections movable relatively to each other, lengthwise of said shaft. For instance, the short horizontal lower portion m (Fig. 5) of said track is formed upon a sleeve segment 29^c (Fig. 7) movable lengthwise between the spaced edges of a wider sleeve segment 29^d which carries the long horizontal upper portion n of the track and is also movable lengthwise of the shaft 28, but held to rotate therewith, as by means of a longitudinal key 29^e (Fig. 8). Rings 29^f rigidly secured to one of the sleeve-segments, and in loose sliding engagement with the other, compel the two segments to remain in contact so that they will complement each other to form a sleeve. Each of the intermediate or connecting portions o of the track-forming flanges is in this case made of two members 29^g having pin-and-slot connections at their adjacent, overlapping ends, while their other ends are pivoted, as at 29^h, to the respective ends of the horizontal flange portions m and n . Each of the sleeve-segments 29^c and 29^d is formed with horizontal circumferential grooves (shown at the upper end in Figs. 7 and 8) forming rack-sections in engagement with normally stationary pinions 44, 44' respectively. The upper portion of the sleeve formed by the segments 29^c, 29^d is also supported by means of bearing balls 28^b associated with the pinion 25 and engaging a sleeve 29ⁱ secured rigidly to the segment 29^d and allowing the segment 29^c to slide lengthwise. This construction also provides an additional means for centering the upper portion of the shaft 28 surrounded by the sleeve 29^c, 29^d. The pinion 28^a prevents any upward movement of the shaft 28.

With the sleeve-segments 29^c, 29^d in the position shown in Figs. 7 to 10 (corresponding to diagram I of Fig. 12), the blades 27^a will be operated in such a way as to stand vertical at the time of exerting their action (in the sector corresponding to the cam-track portion m). By turning the pinions 44, 44' so as to shift the sleeve-segment 29^c with the track portion m up, and the sleeve-segment 29^d with the track-portion n down the same distance, all the track-portions m , n , o may be brought into the same horizontal plane, as indicated in Fig. 11 and in diagram II of Fig. 12. This will cause all the blades, at every point of their travel, to stand inclined, say at 45°, as indicated in said diagram II. A lifting or a lowering effect is obtained according to the direction in which the blade-carrying shaft is rotated. By leaving the track-portion m in its original position, and sliding only the sleeve-

segment 29^d carrying the track-portion n , into the same position as in diagram II, I obtain the position illustrated by diagram III, according to which the blades 27^a, as long as they are in registry with the track-portion n , will remain inclined, say at 45°, and will assume the vertical position (propelling forward or rearward) at the short track-portion m . With this adjustment, the blades will have not only a lifting or lowering effect on the ship at the track-portion n , but they will also propel the ship ahead or astern by their action at m . With the position indicated in diagram II, there is no propelling action either ahead or astern, for the reason that diametrically-opposed blades will have a counter-balancing or neutralizing influence, so far as propulsion ahead or astern is concerned. The cam track, while adjustable to different positions as described, is of course normally stationary during the operation of the propeller, that is, does not share the rotation of the propeller shaft. By building it very light, the propeller structure described above in its special relation to submarines, can be applied very advantageously to other crafts, such as aeroplanes, dirigible balloons, or the like, and their direction determined accordingly, both as to horizontal and vertical steering. Of course, in the case of vessels adapted to travel only on the surface of the water, the propeller generally will not be adjustable for exerting a lifting or lowering effect on the ship.

The arrangement of the cranks 30^b relatively to the track should be such that with the blade-carrying shaft rotating in the normal direction, the strain on the shoe-carrying cranks will be a tension or pulling strain, and not a compression or pushing strain. Fig. 5 shows the blade-axis 41 as moving toward the right with the crank 30^b extending rearwardly, that is to say, toward the left from the blade-axis 41 to the shoe 30, so that the crank will always be under a tension or pulling strain while the shaft rotates in this direction. In the first position shown at the left, the shoe 30 is at the right-hand end of the track-portion n , and the blade 27^a is in a horizontal position. The crank 30^b is inclined at 45° to the left and upwardly from the axis 41. In the next position shown, the shoe 30 is at the middle of the left-hand inclined track-portion o , the crank 30^b has swung till it is about horizontal, and the blade 27^a is in an inclined position, with its upper edge forward, with reference to the direction of rotation. In the next position shown, the shoe 30 is at the left-hand end of the track portion m , and the crank 30^b has swung through an angle of 90° from the first position, to a position in which it is inclined at 45° to the left and downwardly from the axis 41; this of course

has brought the blade 27^a to the vertical position. In the next position illustrated, the shoe 30 has moved up into the second inclined track-portion *o*, and both crank and 5 blade occupy positions intermediate between the first and third positions, and similar to the second position, that is to say, the blade is inclined, with its upper edge forward, in the direction of rotation. 10 Finally, at the extreme right, the shoe 30 is at the left-hand end of the track-portion *n*, and the relative positions of crank 30^b, blade 27^a, and axis 41 are the same as in the position shown at the extreme left. Fig. 5 15 shows the horizontal path 42 of the blade-axis 41 as lying just half-way between the horizontal center-lines of the track-portions *m* and *n*; this is the arrangement which in my opinion will yield the best results. In 20 this case, the length of the crank 30^b will be equal to the hypotenuse of an isosceles right-angled triangle, the other two sides of which are each equal to half the distance (measured vertically) between the two track-portions 25 *m* and *n*.

It will be observed that the short horizontal track-portion *m* is located below the long horizontal track-portion *n*, and as a result of this arrangement, that edge of the 30 blade 27^a which is forward (with reference to the direction of rotation), will be the upper edge of the blade at all times, as will be evident from Fig. 5, and particularly the second, third, and fourth positions shown 35 therein. In other words, during the entire time that the blade passes from the horizontal position to the vertical one, and vice-versa, the blade will be inclined with its upper edge ahead in the direction of rotation, and this inclination will cause the blade to exert a downward push on the water, at the time the blade swings from the horizontal position to the vertical one, or vice-versa, thereby having a tendency to 40 raise the hull out of the water, which is more conducive to efficient action than if the blades tended to force the hull down at the time of their swinging about their axes.

Important advantages are obtained, in 50 the case of the construction illustrated by Fig. 7, by making the cranks 30^b readily detachable from the shanks of the blades, for instance by means of the two-part crank construction indicated in Fig. 5. Upon detaching the small part or cap of the crank, the latter is disconnected from the blades, so that the center-shaft 28 can be removed 55 upwardly, with the entire cam-track and also with the shoes 30 and cranks 30^b, or at least the long or main portions of these cranks.

When using stern propellers, I may either 60 employ them in pairs, at opposite sides of the longitudinal center of the vessel (see Figs. 2, 3, 4 and 6), or a single propeller of

this kind may be used by arranging it in the longitudinal center of the ship.

As regards the slide-blocks or shoes 30, I prefer them to rollers on account of their greater durability, as fully explained in my 70 Letters Patent No. 1,182,014 referred to above.

When propellers are employed in pairs (Figs. 2, 3, 4, and 6), they should rotate in opposite directions, as indicated in Fig. 6. 75 In this case, whenever the two center-shafts 28 of the same pair are adjusted for the purpose described, they should both be turned in the same direction and through the same angle.

Fig. 6 shows that the angle during which the blades are exerting their pushing action on the water or other medium, is about 60°, that is to say, about 30° forward and 30° to the rear of a transverse plane passing through the axis of the propeller, when the ship is being propelled either ahead or astern. When the propeller is operated in such a manner as to swing the ship to port or starboard, the blades will be in their active position within an angle of 60°, of which approximately 30° will be to the left, and 30° to the right of a plane extending longitudinally of the ship and containing the axis of the propeller, that is to say, in this case also the angle during which the blades will be active, will be approximately 60°. When the blades are in their active position, that is to say, with their broad faces perpendicular to their circular line of motion, they act as levers and thus exert a powerful action to propel or steer the ship. During the remainder of their travel, the blades are inactive and proceed edgewise so as to reduce the resistance to their passage through the water or other medium. It will be understood that the individual blades of the same propeller reach their inactive position successively so as to produce a practically continuous action on the water. Since my propeller operates on the principle of a lever, and not by screw action as the usual propellers, I am enabled to utilize the engine power much more efficiently and completely than this is possible with the constructions employed hitherto.

It will be noted that (for the sake of simpler illustration) Fig. 7 does not show the blades 27^a as they will stand during the normal propelling action, but rather as they will stand if the propeller is used for steering. The normal propelling position of the blades is indicated in Figs. 1 to 4 inclusive and in Fig. 6.

Any accidental downward or upward movement of the sleeve-segments 29^c, 29^d is prevented in any suitable manner, and as an example of how this may be accomplished, I have illustrated (Fig. 7) spring-pressed pawls 53 which normally hold the pinions 44,

44' against rotation in either direction. Any appropriate device may be employed for insuring that the parts, especially the sleeve-segments, will always be stopped in the proper position. For instance, each of the pinions 44, 44' may be limited in its turning movement, say by means of a pin 54 projecting into a segmental slot 44'' of the pinion and adapted to arrest the pinion when the end of the slot is reached.

If the pinion 44 engaging the narrow sleeve-segment 29^c were mounted in a stationary bearing, the turning of the center-shaft 28 might carry said segment out of engagement with said pinion, leaving the segment free to move lengthwise. In order to prevent this, I prefer to journal the pinions 44, 44' in a carrier 55 mounted to turn with the shaft 28, so that the pinions will always remain in engagement with the respective sleeve-segments. This arrangement is shown in Fig. 7. The carrier 55 is also shown as serving to support the limiting pins 54 mentioned above. Of course, when the pinions 44, 44' follow the rotation of the sleeve-segments 29^c, 29^d and of the shaft 28, as just described, it is not necessary to employ grooves extending along the entire circumference of the sleeve-segments, but only rack-teeth at the points engaged by the pinions 44, 44'.

Any suitable means (not shown) may be employed for turning the pinions 44, 44' to raise or lower the respective sleeve-segments.

I claim as my invention:

1. A structure adapted for use as a propeller, comprising a rotary member, feathering blades pivoted to said member, blade-swinging members connected with said blades, a normally stationary track for guiding and operating said blade-swinging members, said track including a portion adjustable relatively to the remaining portion of the track, in a direction lengthwise of the axis of said rotary member, the track being further adjustable bodily by turning it about said axis, and means connected with said track to share the turning adjustment thereof and in permanent engagement with said longitudinally movable track portion to effect its adjustment relatively to the remaining portion of the track.

2. A structure adapted for use as a propeller, comprising a rotary member, feathering blades pivoted to said member, blade-swinging members connected with said blades, a normally stationary track for guiding and operating said blade-swinging members, said track including two adjustable portions movable relatively to each other in a direction lengthwise of the axis of said rotary member, a normally stationary shaft co-axial with said rotary member and connected with said track in such a manner, that said track will move bodily with the

shaft as the latter is turned about said axis for adjustment, both of said track portions being provided with teeth, adjusting pinions in engagement with said teeth, and a carrier held to turn with said shaft, and on which said pinions are journaled.

3. A structure adapted for use as a propeller, comprising a rotary member, feathering blades pivoted to said member about axes lying in a plane perpendicular to the axis of said member, blade-swinging members connected with said blades, a normally stationary shaft located within said rotary member and coaxial therewith, means for turning said shaft, two complementary sleeve-segments capable of relative sliding movement lengthwise of said shaft but held to turn therewith and carrying track-portions lying in planes perpendicular to said shaft, intermediate track-portions connected with the first-named track-portions loosely and forming with them a track for guiding and operating said blade-swinging members, and means for effecting relative shifting of the first-named track-portions lengthwise of the shaft.

4. A structure adapted for use as a propeller, comprising a rotary member, feathering blades pivoted to said member about axes lying in a plane perpendicular to the axis of said member, blade-swinging members connected with said blades, a normally stationary track for guiding and operating said blade-swinging members, said track comprising two main portions susceptible of relative adjustment lengthwise of the axis of the rotary member, and two intermediate portions connected loosely with said main portions, and means for effecting relative adjustment of said track portions lengthwise of the axis of the rotary member.

5. A structure adapted for use as a propeller, comprising a rotary member, feathering blades pivoted to said member about axes lying in a plane perpendicular to the axis of said member, blade-swinging members connected with said blades, a normally stationary track for guiding and operating said blade-swinging members, said track comprising two main portions susceptible of relative adjustment lengthwise of the axis of the rotary member, and two intermediate portions each of which consists of two sections overlapping at one end and shiftable relatively to each other to lengthen or shorten such intermediate portion, the other ends of said sections being pivotally connected with the respective main track-portions, and means for effecting relative adjustment of the main track-portions lengthwise of the axis of the rotary member.

6. A structure adapted for use as a propeller, comprising a rotary member, feath-

ering blades pivoted to said member, blade-swinging members connected with said blades, and a normally stationary track for guiding and operating said blade-swinging members, said track including a portion adjustable relatively to the remaining portion of the track, in a direction lengthwise of the axis of said rotary member.

7. A structure adapted for use as a propeller, comprising a rotary member, blades pivoted to said member about transverse axes, blade-swinging members connected with said blades, and a normally stationary track for guiding and operating said blade-swinging members, said track comprising a main portion for holding the blades edge-wise or inactive, and another portion for holding the said blades active or flatwise, the last-named portion being adjustable lengthwise of the axis of said rotary member, to vary the angular position taken by the blades at the time of their active motion.

8. A structure adapted for use as a propeller, comprising a rotary member, blades pivoted to said member about transverse axes, blade-swinging members connected with said blades, and a normally stationary track for guiding and operating said blade-swinging members, said track comprising a main portion of relatively great circumferential extent, and another portion of relatively small circumferential extent, each

of said portions being adjustable independently lengthwise of the axis of the rotary member, to vary the angular position taken by the blades, both when controlled by the track-portion of relatively great circumferential extent, and when passing adjacent to the shorter track-portion.

9. A feathering-blade structure adapted for use as a propeller, comprising a rotary member, feathering blades carried by said member, a non-rotary track operatively related to said blades to give them a feathering motion on their axes as said blades are carried around the track by the rotation of said member, said track and member being relatively adjustable lengthwise of the axis of said member's rotation, and means for effecting such longitudinal adjustment and thereby varying the angle which the blades, when in their active position, form with a plane perpendicular to said axis of rotation.

10. A structure adapted for use as a propeller, comprising a rotary member, feathering blades carried by said member pivotally, blade-swinging members connected with said blades, and a cam-track for guiding and operating said blade-swinging members, said track being adjustable lengthwise of the axis of said rotary member.

In testimony whereof, I have signed this specification.

BAPTISTE ICRE.
